UNITED STATES PATENT OFFICE.

FRANCIS T. LEILICH, OF SAN FRANCISCO, CALIFORNIA.

BED AND CYLINDER PRINTING PRESS.

Application filed December 19, 1923. Serial No. 681,616.

To all whom it may concern:

Be it known that I, FRANCIS T. LEILICH, a citizen of the United States, and a resident of the city and county of San Francisco and State of California, have invented certain new and useful Improvements in Bed and Cylinder Printing Presses, of which the following description, and accompanying drawings, are a full and complete specification.

This invention relates to that class of printing presses in which a flat bed is reciprocated beneath a continuously rotated impression cylinder and embodies certain improvements whereby a larger product of a higher quality is obtained.

It is well known that in machines of the foregoing character in which the type bed is reciprocated by means which engage with it at one side of a central longitudinal line through it, that much trouble and loss of time occurs from the side strains and twisting movements created thereby, and which cause the working up of letters and quads while running.

It is also well known that the speed of machines of this character, more especially those of the perfecting type in which the bed is very heavy, is limited by the difficulty of reversing the movement of the bed, the greater part of the work of which is performed when the reversal means are well toward the end of the movement.

One of the objects of my invention is to reciprocate the type bed of a printing press by means which are continuously engaged with it at, or near, its respective opposite sides and by which it is moved, more particularly during the printing period, at a uniform velocity, and by which it is retarded and accelerated, at each end of its to and fro movement, by the same elements that move it at other times; whereby a perfect parallelism of movement is secured and all side strains and resultant evils are entirely prevented. A valuable feature of the reversing means is the ability, in practicing this invention, to determine the rate of retardation and acceleration of the type bed, and thus distribute more equally the work and strain.

Another of my objects is to secure the most perfect bed register possible which I attain by gearing the impression cylinder positively to the type bed during the printing process, the latter rotating the former

during the printing to the exclusion of all other means.

In presses in which the cylinder is lifted to permit the type bed to return on the non-printing stroke the cylinder driving gear and the intermediate gear engaged therewith run out of correct pitch a large part of the time, causing noise, wear and impaired register. A further object of my invention is to maintain the pitch lines of the several members of the cylinder driving gear train constantly coincident at all times and in all positions of the cylinder thereby preventing said faults, all of which is fully described and claimed in the following specification and illustrated in the accompanying drawings.

In the drawings Fig. 1, is a plan view, with certain parts broken away to show underlying members. Fig. 2, is a side elevation, with certain parts broken away and others in dotted outline for the sake of clearness. Fig. 3, is an end elevation, in cross section. Fig. 4, is an end elevation, in cross section, of an alternative construction. Fig. 5, is an explanatory diagram of the bed movement. Fig. 6, is a plan view, in cross section, of the mechanism for shifting the driving pinion. Fig. 7, is an end elevation of the shifting mechanism, in cross section. Fig. 8, is a side elevation of the means by which the pitch lines of the several members of the gear train for rotating the impression cylinder, at certain times, are maintained coincident at all times and in all positions. Fig. 9, is a side elevation of an alternative construction of said means. Fig. 10, is a side elevation, in detail cross section, showing a method of mounting the vertical member of the before named means, illustrated in Fig. 8, independently of the cylinder shaft.

At one end of a driving shaft 1 is fixed a bevel gear 2, engaged with a bevel gear 3 secured upon one end of a vertical shaft 4, on which is also fixed a spur gear 5 engaged with a gear 6 secured upon a shaft 6^a the gear 6 is engaged with a gear 7 secured upon a shaft 7^a, rotatable once in each complete reciprocation of the type bed. Rigidly fixed upon the shaft 7^a is a crank 8 to which is secured a stud and roller 9, continuously engaged with a slot, or path 10, formed within a slideable body 11, horizontally movable in guides, or ways, 12, 12.

The slideable body, as originally con-

structed, is known as a Scotch yoke, in which, the slot, or path, is straight and of an unvarying contour, whereas in my invention the corresponding slot, or path 10, 5 is, in its preferred form, of a curvilinear path throughout, but it may be partly straight and partly curved at one or both ends if desired, by which a movement is obtained not possible with the said Scotch 10 yoke, as illustrated in the comparative diagram Fig. 5 and hereinafter fully described. To the slideable body 11, is attached a rack 11^a, the teeth of which constantly engage with those of a gear wheel 13 rigidly secured 15 upon a shaft 14. To each of the ends of the latter is fixed one of two gear wheels 15, 15. The latter gear wheels are continuously engaged with the respective bed driving racks 16, 16, rigidly attached to the type 20 bed 17.

In the alternative construction, illustrated in Fig. 4, a single bed driving rack 16^a, is attached to the type bed 17, preferably at, or near, its longitudinal central line, the 25 said rack 16^a engages constantly with a single bed driving gear wheel 15^a, fixed on the same shaft as that on which the gear wheel 15 is secured, both of said gear wheels may be joined together as one element if 30 desired.

To the respective opposite sides of the type bed 17, are secured cylinder driving racks 18, 18, preferably cut in the same bodies of metal in which are cut the bed driving racks 35 16, 16.

Engaging with the racks 18, 18, at certain times, are auxiliary cylinder driving gear wheels 19, 19, one of each secured to the respective opposite ends of the cylinder 20.

40 The cylinder 20, is fixed on a cylinder driving shaft 21, to one of the ends of which is secured a cylinder driving gear wheel 22, which is engaged with an intermediate gear wheel 23, in turn engaged, at certain times, 45 with a driving pinion 24, slidably mounted on the driving shaft 1, and continuously rotatable therewith.

By thus gearing the impression cylinder and type bed together, during the printing 50 operation as above described and shown in the drawings, the said cylinder being continuously rotated a more accurate bed register is obtained than is possible when the cylinder is independently rotated by a separate gear train from the driving shaft. The 55 mechanism for raising and lowering the impression cylinder 20, is as follows:

Fixed on the shaft 6^a, is a cam 25, in the path, 25^a, of which is engaged a cam roll 60 and stud 26 secured upon one end of a lever 27, the other end of which is pivotally engaged with one end of a hooked connection 28, provided with a spur 28^a, the connection 28, engages, normally, with a pin 29^a, on an 65 arm 29, rigidly fixed on a rocking shaft 30.

Secured on the respective opposite ends of the rocking shaft 30 are bodies 31, and 32, respectively provided with cam paths 31^a, 32^a, one of which 31^a, formed in the body 31 is shown in Fig. 2, that in the body 32, being 70 a duplicate of that in the body 31, is not shown.

Engaged with the respective cam paths 31^a, 32^a, are the rollers and studs 31^b, 32^b, fixed on the respective levers 33, 33^a, which are 75 fulcrumed in suitable stationary positions. To the opposite ends of said levers are pivotally attached the respective lower ends of the connections 34, 34^a, to which are similarly attached, at their upper ends, the arms 80 of the upper members 35, 35^a, of the toggle mechanism. The said upper members bear against the respective under sides of the impression bars 36, 36^a, rigidly fixed on the respective columns 37, 37^a, the lower members 38, 38^a, of the toggle mechanism bear 85 against the cylinder shaft bearings 39, 39^a, by which the cylinder 20 is depressed, the weight of the latter being balanced by the usual springs, one of which 40, is shown in 90 Fig. 2.

The device for manually interrupting the reciprocation of the impression cylinder 20, includes a foot lever 41, fixed on one end of a shaft 42, to the opposite end of which is secured an arm 43, provided with a pin 43^a, extending under the end of the hooked connection 28. This device is held in an inoperative position by any suitable resilient means, by which the hooked connection 28, may be lifted from the pin 29^a, on the rocking arm 29, and restored to its inoperative position.

In all printing presses in which the cylinder rotates more than once in a complete reciprocation of the type bed it is lifted to permit the type bed to return on the non-printing stroke, this lifting of the cylinder separates the pitch line of its driving gear wheel from that of the intermediate gear wheel engaged with it, and as said gear wheels, in actual practice, run out of correct pitch nearly two thirds of the running time the faces and flanks of their respective teeth wear to an incorrect shape, when they no longer roll together but slide over each other, with the result that the impression cylinder is rotated by successive impulses which, slight though they may be, cause 110 undue wear, with consequent noise and impaired register.

In mechanisms of the character referred to it is necessary to lift the impression cylinder only sufficiently to permit the return of the type form, whereas in my invention the lift of the cylinder must be great enough to safely clear the points of the respective teeth of the auxiliary gear wheels 19, 19 from those of the cylinder driving racks 130 18, 18.

This amount of lift, in the usual construction, would separate the respective teeth of the cylinder driving gear wheel and intermediate gear wheel engaged therewith, to such a great extent as to be entirely impracticable. It is also necessary, at times, to adjust the cylinder away from the form, in which position the said gear wheels run out of correct pitch all of the time.

10 In this invention I have provided means by which the pitch lines of the several members of the cylinder driving gear train may be maintained coincident at all times and in all positions regardless of the position of 15 the cylinder with respect to the form. Supported around the shaft 21 is a connection 44, illustrated in a preferred form in Figs. 2, 8 and 10, in which said connection 44, is movably mounted upon a support 45 secured 20 to the cylinder shaft bearing 39. It is desirable that the support 45 be independent of contact with the cylinder shaft 21, to avoid unnecessary wear and friction.

While the connection 44 may be mounted 25 directly upon the shaft 21, or upon any part moved by the hereinafter described means for lifting the said cylinder shaft 21. I prefer to mount it as illustrated in Figs. 2, 8, and 10, for the reasons before stated relative to the support 45.

Fixed upon the connection 44, is a stud 46, upon which is rotatably mounted the intermediate gear wheel 23, engaged with the cylinder driving gear wheel 22, which is engaged, at certain times, with the driving pinion 24. The respective pitch lines of said gears are maintained coincident at all times and in all positions by a link 47, pivotally secured to the lower end of the connection 44, and at the other end to a suitable stationary part. In the alternative construction shown in Fig. 9, the same effect is obtained by forming in the lower end of the connection 44, a curved slot 47^a, in which is a curved block 47^b pivotally secured, as 40 a screw 47^c, to a suitably fixed part. In order to maintain the pitch lines of the intermediate gear 23, and driving pinion 24, always coincident the centre of the stud 46, must move in an arc, see Fig. 8, the radius of which equals the sum of the radii of said gear 23 and pinion 24. In Figs. 1 and 45 8 the link 47 is shown as pivotally attached to the connection 44 below the stud 46, and as shorter than the combined radii of the intermediate gear wheel 23 and the driving pinion 24, the arc described by the moving centre of the link 47 is therefore more convex than that described by the centre of the 50 stud 46 which is necessary to maintain the pitch lines of said gear 23 and pinion 24 always coincident. The difference in the convexity of the aforesaid arcs is therefore governed by the distance between the centre 55 of the stud 46 and the centre of the link 47,

the greater distance between said points requiring a shorter radius of the link 47 and consequent greater convexity of the arc described by it. The foregoing applies also to the alternative construction shown in Fig. 9 the curve 47^a being obtained in like manner as before set forth.

The means by which the impression cylinder 20 is engaged with, and disengaged from, the type bed 17 before and after the printing period, is as follows:

The driving pinion 24 is constrained to rotate with the driving shaft 1 by a spline 7^a fixed therein, or in any other suitable manner. The driving pinion 24 is provided with a collar 48 engaged by rollers or blocks 49 pivotally attached to a yoke 50, fixed on a shaft 51, which is constrained to a sliding movement by a coupling block 52 rigidly fixed upon the shaft 51. Secured in like manner to the coupling block 52 is a shaft 53 the free end of which is guided in a bracket 53^a.

To the shaft 51 is also fixed a block 54 to which is pivotally secured a stud and roller or trunnion block 55 engaged with a yoked lever 56 fixed on a shaft 57. To the opposite end of the latter is secured a lever 58 to which is fixed a stud and roller 59 engaging with a cam path 60, formed in the body 31, secured on the shaft 30.

In the operation of my invention power is applied to the driving shaft 1, rotating, through the gear train 2, 3, 5, 6 the gear wheel 7, and thereby reciprocating, through the connected elements, before described, the type bed 17 once in each cycle of motion, the impression cylinder 20 being constantly rotated twice in said cycle of motion. Referring to Fig. 2, the view is from the gear side, of the press and shows it as at the end of the printing stroke, with the impression cylinder 20 engaged, through the auxiliary gear wheels 19, 19, with the cylinder driving racks 18, 18, secured to the type bed 17, and with the driving pinion 24 disengaged from the intermediate gear wheel 23, thereby permitting the cylinder 20 to be actuated solely by its operative engagement with the type bed 17. Heretofore in certain mechanisms in which crank driven means have been used for reciprocating the type bed the impression cylinder has been geared to the latter, during the printing period, but, as is well known, the bed movement obtained by such means is variable and at no time constant. This irregular bed movement caused gray, or unevenly inked sheets to occur, as less time was afforded, during the faster parts of the bed movement, for the inking rollers to take the ink from the plate and transfer it to the type form, less time was also afforded for the striking of the ink on the sheet, these faults, or defects, were particularly noticeable when the type

matter was heavy, requiring a good deal of ink. In all printing presses in which the type bed is reciprocated by means which engage with it at one side of a central longitudinal line through it side strains and twisting movements occur, which may be caused by the position of a form when placed to one side of the bed, or by a form in which the impression is heavier on one side than the other, due to the make ready. The before named defects are more apparent when the heavier impression is opposite to the point of engagement of the driving means with the type bed, the pull of the plate rollers also contributes in setting up strains. These twisting movements cause the working up of quads and letters and loss of time in stoppage of the press to correct them.

20 In the development of the reciprocating flat bed printing press the reversal of the movement has always been a difficult problem and one limiting its speed, especially in large presses carrying heavy forms thereby necessitating a heavy increase in the static weight of the press to absorb the kinetic energy, and keep the press in position on the floor. In all presses known to me the retardation and acceleration of the type bed

25 has been accomplished by means in which the work and strain has been irregularly distributed, the greater part of the retardation being done during the latter half of the reversing period, and the acceleration during the latter half of that period. In my invention the retarding and accelerating of the type bed is accomplished by the same means that drive it to and fro. The speed of the retarding and accelerating movements may be made to suit the requirements of any particular type of press and the labor and strain of reversing the direction of the bed movement better equalized, or distributed, over the reversal period and the shock or jar upon the press at the respective ends of said movements greatly decreased. By thus moving the type bed to and fro and reversing its direction of movement by a single means

30 positively and continuously engaged with it at its respective opposite sides I secure perfect parallelism of movement, which is not affected by any position of either the form or impression, and also secure a better distribution of the reversal strain.

35 In conjunction with the above I also obtain the most perfect bed register possible by gearing the impression cylinder directly with the type bed during the printing operation to the exclusion of all other means. In order that this invention may be clearly understood I have illustrated, in Fig. 5, in a comparative diagrammatic form the difference in construction between the ordinary Scotch yoke or cross head movement and

the construction of this application. In the diagram Fig. 5 the centre of the crank stud and roller 9, attached to the crank 8, describes in one half of its revolution the arc A, A, which is divided into twenty four ordinal spaces of fifteen degrees each, to correspond with the three hundred and sixty degrees of one revolution of the impression cylinder, which rotates twice in each reciprocation of the type bed. At the top of the sheet are drawn three horizontal lines B, B¹, B², each equal in length to the chord of the arc A, A, from the centre of said arc dotted radial lines extend to its circumference and include spaces of fifteen degrees each. Vertical lines F extend from the points of contact of the respective dotted radial lines with the arc A, A, between the horizontal lines B and B² and from C to D, at the left is indicated the period in which the reversal of movement occurs and from D to C¹ the major part of the movement. To the right of the sheet, the vertical lines L, m, n, o, p, between C¹ and D¹ and B¹ and B³ indicate the reversal period at the opposite end of the major movement. These ordinal spaces are all unequal and illustrate the variations in the crank and cross head movement, also called a Scotch yoke. Between the horizontal lines B and B¹ and the vertical lines D and C¹, the vertical lines G are all equal and uniform and illustrate the major part of the movement obtained by my invention and also show the difference between it and the Scotch yoke movement shown between B¹ and B².

The ordinal spaces between the horizontal lines B and B¹, and C and D, and C¹ and D¹, at the respective ends thereof are the same as in the Scotch yoke movement and are for the same purpose, to wit, retarding and accelerating the movement of the bed, at each end of the reciprocation. In the Scotch yoke movement the slot or path, engaged by the roller 9 is straight, as shown by the solid line C¹, and always imparts a movement to a connected body that is at no time constant and it is a prime object of my invention to move such a connected body by a crank during a predetermined time, or times, at an equal or uniform velocity, as will now be described. The stud and roller 9 is shown as leaving the path H at the end of the printing period, the arrow indicating the direction of the movement, and about entering the straight part of the path C¹ between A and a.

The dotted curve H along which the stud and roller 9 must pass to impart to the bed the equal movement desired is plotted as follows:

The horizontal dot and dash lines b, c, d, e, f, and g, proceed from the contact points of the vertical ordinal lines F with the arc A, A, and extend across the vertical line C¹

to the right. The variations b^1 to f^1 inclusive, between the vertical dotted lines G and the full vertical or ordinal lines F are shown on the horizontal line B^1 and indicate the extent of the deviation from the straight vertical line C^1 of the Scotch yoke movement necessary to obtain the equal and uniform movement of this invention, as illustrated between the horizontal lines B , B^1 10 and the vertical lines C^1 and D . The variations b^1 to f^1 inclusive are now set off from the vertical line C^1 , to the right on the respective horizontal dot and dash lines b to f inclusive and thereon marked, by a cross 15 in the drawing. Through these marks is then drawn the heavy dotted curve H commencing at a on the vertical line C^1 and ending at g on the same line, the curve H indicates the centre of the path through 20 which the stud and roller 9 must pass to afford the equal and uniform movement desired. The movement imparted to the slideable body 11, after passing the vertical central line E , is a repetition in reverse order 25 of that described and therefore requires no further elucidation. In the practical application of my invention, I have illustrated in Fig. 5 a preferred form of means for reversing the movement of the type bed in 30 which the strain, or labor, is more evenly distributed over the retarding and accelerating period, whereby the kinetic energy of the type bed remaining at the end of the reciprocation is greatly reduced and higher 35 speed made possible with the same static weight of the press. In the preferred form of reversal means between the horizontal lines B^1 and B^2 and the vertical lines C^1 , D^1 , is extended a shorter horizontal line B^3 , between the latter line and the line B^2 are 40 vertically extended the ordinal lines L^1 , m^1 , n^1 , o^1 , p^1 , each enclosing unequal spaces. These lines are arbitrarily determined and illustrate the difference between the ordinal 45 lines L to D^1 of the Scotch yoke movement and the ordinal lines L^1 , m^1 , n^1 , o^1 , p^1 , to D^1 of my invention. In the Scotch yoke movement and also in the crank and connection mechanism once used, the position, or included 50 spaces between the lines aforesaid were dependent upon, and affected by, the crank radius in the former device, and in the latter mechanism by the length of the connection also, whereas in my invention the spacing of said lines is determined and fixed at will to suit the varying requirements of different sizes of presses. From the respective points of contact of the vertical lines L to D^1 inclusive with the respective radial dotted lines at the arc A , A , horizontal lines k^1 , k^2 , k^3 , k^4 , k^5 extend to the right across the vertical line C^1 . Upon each of these lines respectively are then set off from the vertical line C^1 to the right 55 thereof, the several distances shown between

the dotted ordinal lines L to p inclusive and the solid lines b^1 to p^1 inclusive, as shown between the horizontal lines B^2 and B^3 , and then marked, as by a cross, on the respective horizontal lines k^1 to k^5 inclusive. 70

Through the aforesaid marks is then drawn the light dotted line K , commencing at the termination of the heavy dotted line H at a , and passing through each of said cross marks to k^5 where it recedes to the 75 vertical line C^1 at the bottom as shown in Fig. 5.

This line K illustrates the centre of the path in which the stud and roller 9 moves during the retarding and accelerating of 80 the type bed. The light dotted line K is shown as straight because of the difficulty in showing on so small a scale the slight variations in curvature, the outline, or contour, of said line is determined entirely 85 by the relative number of degrees included in the respective ordinal spaces L^1 to p^1 , the line K platted therefrom may be either wholly curvilinear or partly straight. In the preferred form of retarding means as 90 illustrated in Fig. 5, it will be seen that during one quarter of the movement of the crank stud 9 the speed of the type bed has been reduced to three quarters of that of its major travel, at one half of the movement of said crank stud to less than one half of said speed and at three quarters of the movement of said crank stud to one quarter of the speed of the type bed during its major travel, whereby the kinetic energy of the 95 type bed is very greatly reduced, higher speed made possible and a great reduction in the static weight now necessary to absorb said energy ensured.

I wish it understood that the ordinals 100 L^1 , to p^1 inclusive can be changed at the will of the designer and that in Fig. 5, they, as well as all the drawings are illustrative only. In Fig. 5, in the preferred form of reversal of the reciprocation the 105 stud and roller 9 is shown on the retarding end of the printing stroke, but as the plating of the accelerating end of the movement is the same no further illustration is thought necessary, and as the preferred 110 manner of moving the bed on the non-printing stroke and reversing its movement is also the same as on the printing stroke before described further illustration of the latter stroke is also deemed superfluous. 115

In constructing an operative mechanism it will be found desirable to plat the diagram Fig. 5, full size, with many more ordinals of fewer included degrees, in order that the movement imparted to the slideable 120 body 11 and connected type bed should be as uniform as possible throughout the major part of the movement. Perfect mechanical accuracy in the plating of the curve H is, however, not absolutely necessary in secur- 125 130

ing perfection of bed register, because the impression cylinder 20 and type bed 17 are geared together positively during the printing operation, the latter actuating the former exclusively during said operation, it is obvious therefore that both printing elements must move at exactly the same velocity.

I have however, provided mechanical means for plating the curve H in Fig. 5 with mathematical accuracy, disclosure of which is reserved for a separate application. Continuing the description of the operation of my invention the printing of the sheet

10 being completed, the cylinder driving racks, 18, 18 move out of engagement with the auxiliary gear wheels 19, 19, prior to which time the driving pinion 24 is moved into engagement with the intermediate gear 23.

15 The type bed 17 is then slowed down and reversed in the direction of its movement, the impression cylinder 20 has meanwhile been raised to permit the said type bed 17 to be moved on the return stroke, at the

20 end of which it is again retarded and reversed in the direction of its movement and begins again on the printing stroke the driving pinion 24 having previously been disengaged from the intermediate gear wheel 23 as shown in Fig. 1. The driving pinion 24 is shifted into and out of engagement with the intermediate gear wheel 23 during the time that the type bed 17 is moving on the printing stroke. The cylinder driving

25 rack 18, 18, attached to the type bed 17, are engaged or disengaged, with and from the auxiliary gear wheels 19, 19, just prior to the time that the driving pinion 24 is shifted, as before described, and when the type bed 17 is moving, on the printing stroke at a rectilinear velocity which is equal to the peripheral velocity of the printing surface of the cylinder. The suspension of the reciprocation of the said cylinder is accomplished by the devices shown and described, in the usual manner, and needs no specific description.

30 While it is not necessary in practicing my invention, that the major part of the non-printing, or return stroke should be at the same uniform and equal rate of speed as that of the printing stroke, I prefer that it should be so, as a better inking of the type form is secured and gray sheets and consequent double rolling of said form avoided. The mechanism by which the impression cylinder is depressed, or lowered, to a printing position differs from that used in other constructions for a like purpose, in that it has an additional function, that of shifting the driving pinion 24 into and out of engagement with the intermediate gear wheel 23 before and after the printing period.

35 In the operation of the cylinder depress-

ing mechanism, toward the end of the return stroke the cylinder starts to descend, completing its movement before the cylinder driving racks 18, 18, engage with the auxiliary gear wheels 19, 19, on the printing 70 stroke and as the driving pinion 24 must not be shifted out of engagement with the intermediate gear wheel before the said racks 18, 18, are engaged with the said gear wheels 19, 19, it is obvious that the cylinder 75 depressing mechanism must be competent to perform the two functions without interfering with each other.

After the printing of the sheet and before the auxiliary gear wheels 19, 19 are disengaged from the cylinder driving racks 18, 18, the driving pinion 24 is shifted into engagement with the intermediate gear wheel 23, the cylinder 20 is then raised to its highest position, by the springs 40, 40, one only 80 of which is shown, in Fig. 2, and rotated by the gear train 22, 23, and 24. This shifting of the driving pinion 24, at certain times, is accomplished by means in which the members 31, Figs. 2, 6, and 7 is provided with 85 two cam paths 31^a and 60 respectively. The cam path 31^a is formed with a portion of its path concentric and of sufficient length to allow further movement of the body 31 and thereby permit the cam 60 to shift the driving pinion 24 without further movement of the cylinder depressing mechanism.

90 This shifting of the pinion 24 is therefore performed by the several connecting members interposed between said pinion 24 100 and the cam path 60, by which they are actuated, when the said depressing mechanism is at rest. The description aforesaid relative to the formation of the cam path 31^a 105 in the body 31 also applies to the similar cam path in the body 32, which is not shown. As, in my invention, the impression cylinder 20, must return to its highest position when the tripping device shown in plan in Fig. 1 is used and as the cylinder lifting springs 110 40, 40, are prevented from doing so because of the positive engagement of the cylinder depressing mechanism with the cam paths 31^a, 32^b, I have provided the hooked lever 28 with a spur 28^a of sufficient length that when 115

said device is used to lift the hooked connection 28 out of engagement with the stud 29^a the arm 29 will be moved to the full extent of the movement of said hooked connection by the spur 28^a contacting with the pin 29^a on the arm 29 thereby turning the bodies 31 and 32 thus permitting the lifting 120 of the cylinder 20 to its highest position and obviating all danger of breaking the teeth of the cylinder driving racks 18, 18, and auxiliary gear wheels 19, 19.

125 The tripping or suspension of the cylinder reciprocation, at will, is accomplished in the usual manner by the devices shown, in plan in Fig. 5, and hereinbefore described. I 130

have omitted from the drawings many of the necessary elements of an operative printing press as forming no part of my invention, and while I have illustrated and

5 described it in a preferred form of construction, I do not wish to be understood as limiting myself thereto, as many modifications may be made within its scope without departing from its spirit.

10 My invention resides not only in the novel construction, combination and arrangement of the mechanism and its members, as shown and described and their equivalents, but broadly and more particularly as follows:

15 15 In means for completely reciprocating the type bed by the same elements which move it during the major part of the reciprocation and which are in continuous operative engagement with the type bed at, or near, 20 its respective opposite sides, by which perfect parallelism of movement is secured and also by which the work and strain of accelerating and retarding the type bed is distributed more evenly over the period in 25 which said work is done.

In means for reciprocating the type bed, as before set forth, in combination with mechanism for moving the impression cylinder into a position to be operatively engaged 30 with the type bed before the beginning of the printing operation and out of said position after said operation is completed, by which both printing elements are moved at the same velocity during the printing operation and the greatest possible accuracy 35 of bed register is secured.

40 In means for reciprocating the type bed in which a rotated crank is an element for imparting to the type bed a uniform movement during the printing period.

In means for reciprocating the type bed which include a rotated crank and a slideable body provided with a path of varying contour engaged by the crank.

45 In means for maintaining the pitch lines of the cylinder driving gear train coincident at all times and in all positions.

I claim:

50 1. A type bed, and means for reciprocating it, which include a horizontally rotated crank and a slideable member provided with a path of varying contour with which the crank is always engaged and by which said member is moved to and fro.

55 2. A combination as called for in claim 1 in which the member is horizontally slideable.

60 3. A type bed, and means, which include a horizontally rotated crank a slideable member engaged with the latter and reciprocated by it and elements actuated by the slideable member and operatively engaged with the type bed, for moving said type bed, during the major part of the printing stroke, at a uniform velocity.

4. A type bed, and means for reciprocating it, which include a crank, a horizontally slideable member provided with a path of varying contour with which the crank is engaged, a rack rigidly attached to the slideable member, a gear wheel continuously engaged with the rack, a rack rigidly attached to the type bed, and a gear wheel operatively engaged with the first named gear wheel and continuously engaged with the latter rack. 70

5. A type bed, and means for moving it to and fro at a uniform velocity, during a predetermined time, and for reversing the direction of its movement, which include a plurality of gear wheels rotated in fixed 80 positions and in continuous operative engagement with the respective opposite sides of said type bed.

6. A type bed, and means for reciprocating it at a predetermined time, at a uniform 85 velocity, which include among its elements two bed driving racks rigidly attached to the type bed, one at, or near, each of its two sides, and two gear wheels respectively and continuously engaged with said racks; whereby the said type bed is moved at a uniform velocity during the major part of the printing stroke, and its movement retarded and reversed by the same means 90 that move it to and fro.

7. A type bed, means for reciprocating it which include a crank and a slideable member continuously engaged therewith, an impression cylinder and mechanism for moving the cylinder into a position to operatively engage with the type bed, during the major part of the printing stroke; whereby the respective printing surfaces of the type bed and impression cylinder, are then moved 100 at the same velocity.

8. A combination as called for in claim 7 in which the slideable member is provided with a path of varying contour.

9. A type bed, bed driving racks attached thereto, one at, or near, each of the two sides thereof, means for reciprocating the type bed which are continuously engaged with said racks, an impression cylinder, auxiliary gear wheels secured thereto, one at each end thereof, cylinder driving racks 110 attached to the type bed, one at each of the two sides thereof, and mechanism for moving said gear wheels into and out of the path of said cylinder driving racks at predetermined times.

10. A type bed, bed driving racks attached thereto, one at, or near, each of the two sides thereof, means for reciprocating the type bed which are continuously engaged with the bed driving racks, an impression cylinder, auxiliary gear wheels secured thereto, one at each end thereof, cylinder driving racks attached to the type bed, one at each of the two sides thereof, means for rotating the cylinder 125 which include an intermediate gear wheel 130

- and a slidable driving pinion engaged with the latter, at certain times, mechanism for moving the auxiliary gear wheels into and out of the path of the cylinder driving racks, 5 and means, actuated by said mechanism, for sliding the driving pinion into and out of engagement with the intermediate gear wheel, at predetermined times; whereby, when the driving pinion is engaged with the 10 intermediate gear wheel, the cylinder is rotated by the said driving pinion and when disengaged therefrom said cylinder is rotated by its operative engagement with the type bed.
- 15 11. A combination as called for in claim 10 which includes manually operated devices for suspending, at will, the operation of said mechanism; whereby the cylinder is continuously rotated by the driving pinion, during 20 such suspension.
12. A type bed, means for moving it during the major part of the printing stroke at a uniform velocity and which are continuously engaged with the type bed at, or near, 25 its respective opposite sides, an impression cylinder, and mechanism for moving the latter into and out of positive operative engagement with the type bed; whereby when the type bed and cylinder are in such engagement their respective impression surfaces are moved at the same velocity.
13. A combination as called for in claim 12, which includes in the means for moving the type bed a crank and a slidable member. 35
14. A combination as called for in claim 12, which includes in the means for moving the type bed a crank and a slidable member provided with a path of varying contour.
15. A type bed, means for reciprocating it 40 which include a crank and a horizontally slidable member provided with a path of varying contour engaged by the crank, an impression cylinder, means for rotating it, at certain times, which include a slidable driving pinion, mechanism for moving the cylinder into and out of operative engagement with the type bed at predetermined times and means, actuated by said mechanism for sliding the driving pinion into and 45 out of operative engagement with the impression cylinder, by which the latter is rotated, during the nonprinting period, by its operative engagement with the driving pinion and, during the printing period, by its operative engagement with the type bed; 50 whereby the printing surfaces of the type bed and impression cylinder are moved at the same velocity during the printing period.
16. A type bed, means, which are in constant operative engagement with it at, or near, its respective opposite sides, for completely reciprocating it, an impression cylinder, mechanism for moving it into a position to be operatively engaged with the type bed and for removing it therefrom at pre- 55 determined times, a cylinder driving gear wheel, operatively attached to the cylinder, an intermediate gear wheel directly engaged with said driving gear wheel, and means for maintaining the pitch lines of both of said gear wheels coincident at all times and in all 70 positions.
17. In a combination as called for in claim 16 devices for manually suspending, at will, the reciprocation of said mechanism. 75
18. A cylinder driving gear wheel, an intermediate gear wheel directly engaged therewith, mechanism for vertically reciprocating the first named gear wheel, at predetermined times, which includes positive means for depressing it and resilient means for raising it, a connection movably mounted upon a part moved by said mechanism, and a stud fixed upon the connection on which the intermediate gear wheel is rotatably mounted, for maintaining the pitch lines of both said gear wheels coincident at all times and in all positions. 80
19. A cylinder driving gear wheel, an intermediate gear wheel directly engaged 90 therewith, mechanism for vertically reciprocating the first named gear wheel, at predetermined times, means for maintaining the pitch lines of both said gear wheels coincident at all times and in all positions, a driving pinion engaged at certain times with the intermediate gear wheel, and elements cooperating with said means, for maintaining the pitch lines of said intermediate gear wheel and driving pinion coincident at all times 95 and in all positions.
20. A cylinder driving gear wheel, an intermediate gear wheel engaged therewith, mechanism for vertically reciprocating the first named gear wheel, at predetermined times, a connection movably mounted upon a part moved by said mechanism, a stud fixed upon the connection upon which the intermediate gear wheel is rotatably mounted, for maintaining the pitch lines of both said gear wheels coincident at all times and in all positions, a driving pinion engaged at certain times with the intermediate gear wheel, and means for controlling the connection and thereby causing the stud, 100 upon which the intermediate gear wheel is rotated, to move in an arc concentric to the centre of the driving pinion; whereby the pitch line of the latter coincides with that of said intermediate gear wheel at all times and in all positions. 105
21. A cylinder shaft, a driving gear wheel rigidly fixed on it, an intermediate gear wheel directly engaged with the first gear wheel, mechanism for vertically reciprocating the first named gear wheel which includes positive means for depressing it and resilient means for raising it, at predetermined times, and means for maintaining the pitch lines of both said gear wheels 110 115 120 125 130

coincident at all times and in all positions.

22. A cylinder driving gear wheel, a shaft upon which it is rigidly fixed, an intermediate gear wheel engaged with the cylinder driving gear wheel, a connection, supported around the shaft, upon which the intermediate gear wheel is rotatably mounted, mechanism for vertically reciprocating the gear wheel first named which includes positive means for depressing it and resilient means for raising it, and means including said connection for maintaining the pitch lines of both said gear wheels coincident at all times and in all positions.

15 23. A combination as called for in claim 22 in which the connection is supported around the shaft independently of it.

24. A cylinder, a shaft upon which it is rigidly secured, a cylinder driving gear wheel fixed, in like manner, upon the shaft, a connection supported around the shaft, an intermediate gear wheel rotatably mounted on the connection and engaged with the former gear wheel, a slidable driving pinion engaged, at certain times with the intermediate gear wheel, a type bed, means for reciprocating it, mechanism for vertically reciprocating the cylinder, at predetermined times, to move it into, and out of, a position to be operatively engaged with, and disengaged from, said type bed, means, actuated by said mechanism, for sliding the driving pinion into and out of engagement with the said intermediate gear wheel at predetermined times; whereby the cylinder is rotated by the driving pinion when it is en-

gaged with the said intermediate gear wheel, and is partially rotated by its operative engagement with the type bed when the said driving pinion is disengaged from 40 said intermediate gear wheel.

25. In a combination as called for in claim 24 manually operated devices for suspending, at will, the reciprocation of said mechanism; whereby the cylinder is then 45 rotated entirely by the driving pinion during said suspension.

26. An intermediate gear wheel, mechanism for vertically reciprocating it, a driving shaft, a driving pinion slideable on 50 the latter, for rotating the gear wheel at certain times, means, connected with said mechanism, by which the sliding of the driving pinion into, and out of, engagement with the intermediate gear wheel is completed after the reciprocation of said gear wheel has ceased, and further means for continuing the rotation of said gear wheel after said driving pinion is disengaged 55 from it.

27. A type bed, and means for reciprocating it, which include a rotated crank bearing a stud, and a path of varying contour formed in a member operatively connected to the type bed in which the stud is moved, and for retarding said type bed at each of the ends of its reciprocation at a rate of movement determined by the variation in said path along which the said crank stud is moved when retarding said type bed. 60 65 70
